CLAIM

The ornamental design for a cable breakout enclosure, as shown and described.

DESCRIPTION

FIG. 1 is a perspective view of a first embodiment of a cable breakout enclosure showing my new design;
FIG. 2 is a front view thereof;
FIG. 3 is a rear view thereof;
FIG. 4 is a side view thereof;
FIG. 5 is an opposite side view thereof;
FIG. 6 is a bottom view thereof;
FIG. 7 is a top view thereof;
FIG. 8 is a perspective view of a second embodiment of a cable breakout enclosure showing my new design;
FIG. 9 is a front view thereof;
FIG. 10 is a rear view thereof;
FIG. 11 is a side view thereof;
FIG. 12 is an opposite side view thereof;
FIG. 13 is a bottom view thereof; and,
FIG. 14 is a top view thereof.

The outermost broken lines immediately adjacent to the full line showing of the claimed design represent the bounds of the claimed design while all other broken lines are directed to environment and are for illustrative purposes only; the broken lines form no part of the claimed design.

1 Claim, 12 Drawing Sheets
